UNITED STATES PATENT OFFICE.

JOSEPH J. VORHES AND HIRAM CRISMAN, OF SENECA, KANSAS.

CAR-DOOR.

No. 843,647.

Specification of Letters Patent.

Patented Feb. 12, 1907.

Application filed March 7, 1906. Serial No. 304,693.

To all whom it may concern:

Be it known that we, JOSEPH J. VORHES and HIRAM CRISMAN, citizens of the United States, residing at Seneca, in the county of 5 Nemaha and State of Kansas, have invented certain new and useful Improvements in Car-Doors, of which the following is a specification.

This invention relates to improvements in 10 doors for railway freight-cars, and especially to that class of doors known as "grain-doors," inasmuch as they are especially adapted for use in connection with grain loaded in bulk.

15 The especial objects of the improvements which form the subject-matter of this application are the production of grain-tight doors of simple, durable, and economical construction, which are easily operated in closing 20 or opening, in which the weight is sustained by iron rods in a manner that facilitates the movements of the doors, in which quickly-operated locking means are provided, in which the doors can be readily swung out of 25 position when not in use, in which the doors cannot become detached and lost, and in which various advantages are conserved not necessary to mention, because apparent to those skilled in the art.

30 In the accompanying drawings, which form a part of this application, Figure 1 shows in side elevation a portion of a grain-car equipped with our doors, the latter being shown in closed and locked position. Fig. 2 35 is a view of the parts shown in Fig. 1 as they appear from within the car. Fig. 3 shows the doors in an opening position. Fig. 4 shows the manner of removing and suspending the doors. Fig. 5 is a fragmentary 40 detail showing a door folded up against the car-roof.

Referring to the details of the drawing, A represents one of the side walls of a box-car of 45 ordinary construction, in which there is the usual opening or doorway a'.

B B' represent, respectively, the doors or door-sections, which together form a closure for the opening a' and for the purposes of this description will be respectively designated as the "outer" door and the "inner" door. As shown, these doors are built of two courses of boards laid at right angles to each other, secured together in any preferred.

manner and reinforced along their bottom edges with iron wear-plates; but it will be understood they may be constructed entirely of metal, if desired. When in closed position, these doors are arranged so that the forward edge of the outer door overlaps the inner door a foot or more, thus forming at the center of the doorway an overlap-joint, which contributes to the tightness of the closure. The forward edge of the inner door is detachably interlocked with the outer door by the hook-bars b¹⁷, which are rigidly bolted to the 60 door B' and engage the U-shaped members b¹⁸, which are correspondingly secured to the inner face of the door B, as shown in Fig. 1. The forward edge of the outer door is detachably interlocked with the outer face of the 65 inner door by a locking-bar b², which is partially rotatable in sockets b⁴, fixed in the door B' and projecting outwardly therefrom to form bearings for the outwardly-bent portions b³ of the locking-bar. The lower end of 70 the locking-bar is bent horizontally to form a handle b⁶, by which the bar may be readily turned in its bearings. Means may be provided whereby the handle may be locked; but as such means form no part of this invention 75 they are not shown. The locking-bar is engaged by the horizontal hook members b⁵, which are rigidly secured to the door B and have their hook portions extending beyond the edge of the door and passing below the 80 locking-bar. U-shaped members b²⁰, rigidly secured to the door B, also engage the locking-bar by having their projecting portions bent downwardly, so as to overlie the bar. The latter is therefore embraced on both 85 sides by b⁵ and b²⁰, thus forming double 90 interlocking means, the efficiency of which will be apparent.

At the center of each of the doors and on opposite sides thereof square sheet-iron plates 95 b⁶ are securely bolted. Where the doors are of metal, these plates may be dispensed with, as their function is to furnish suitable reinforced bearings and attaching means for the hanging-rods and their connections to be 100 described. Rotatably mounted in the plates b⁶ and projecting from the inner faces of the doors are eyebolts b⁸ b⁸, which are engaged by eyes formed on the lower ends of the hanging rods b⁷, the upper ends of which are furnished 105 with eyes which engage the eyebolts a³, fixed

in the upper frame-timbers of the car, each bar and its connections thus providing a swinging support for a door which freely permits the various movements and adjustments incident to the operation of the latter. On the squared portion of each eyebolt b^8 is mounted a ratchet-plate b^{10} , which is formed with a handle b^{11} and is adapted to be engaged and held by a pawl b^{12} , pivoted on the plate b^9 . This ratchet-plate has a twofold function in that by turning the eyebolt b^8 on its axis it adjusts the latter to the length of the bar b^7 , thus maintaining the latter at a position of greatest efficiency relative to the door, and when in the opening of the doors the doors are raised, as shown in Fig. 3, they will be held in such position by turning the eyebolts from the position shown in Fig. 2 toward the outer edge of the doors, all of which will be readily apparent.

At the upper and inner corners of the doors we bolt square sheet-iron plates b^{15} , in which are rotatably mounted eyebolts b^{14} , the eyes of which are loosely engaged by eyes on the lower ends of the bars b^{13} , the upper ends of which are loosely engaged by eyes in brackets a^4 , which are so secured to the overhead framing-timbers of the car as to stand outwardly from the timbers a sufficient distance to permit the doors to swing freely under the bars, as shown in Fig. 4. To facilitate the movements of the members $b^{13} b^{14}$, we preferably bevel or chamfer off the corners of the doors, as at b^{16} .

When the doors are not in use, they are hung at the inner side of the car by hooking the members b^{17} of door B' into the members a^5 , secured to the overhead car-framing and the members b^{20} of door B over the hooks a^6 , or they may be swung up to the car-ceiling and held by the hangers a^7 , as shown in Fig. 5.

To set up the doors in operative position, they are unhooked from their respective keepers a^7 , a^8 , and a^5 and are allowed to swing down, the rods $b^7 b^{13}$ sustaining their weight into the position shown at the right hand of Fig. 4. The operator brings each door to an upright position (shown in Fig. 3 with their edges overlapped) and hooks together the members $b^{17} b^{18}$. He then pushes inwardly the projecting edges of the doors until they are parallel, when he turns the locking-bar in its bearings, thus bringing the portions between the bends b^3 under the members b^{20} and over the members b^5 , as shown in Fig. 1. To open the doors, when used as grain-doors the operator reverses the movement of the locking-bar, whereupon the outward pressure of the grain in the car will push the doors to the position shown in Fig. 3, thus forming a triangular opening at the bottom of the doors, through which a portion of the grain passes into a suitable receptacle arranged therefor. When the pressure is relieved, the

operator unhooks the members $b^{17} b^{18}$ and swings the doors into the positions shown in Fig. 4.

It will be noted that when the doors are closed the bars b^7 , being substantially in vertical alinement with the eyebolts, resist any vertical movements of the doors incident to the jolting of the cars and that lateral movements are resisted by the bars b^{13} , thus effecting practically grain-tight joints when considered in connection with the pressure of the grain within the car. It is manifest that the same doors, if made to fill the doorway a' , would form an effective closure for any kind of freight-car and with a suitable lock on the bar b^2 would form a greater protection against car-burglary than most of the horizontally-sliding doors in common use.

Various modifications may be made in the details of the invention herein described without departure from its principles. Hence we do not wish to be limited in our patent to details; but

We claim—

1. Means for closing an opening in a car or other supporting structure, consisting of two complementary door-sections, means for detachably interlocking the sections, hanging bars loosely connected with the middle portion and one corner of each section and loosely connected with the structures.

2. Means for closing an opening in a car or other supporting structure, consisting of two complementary door-sections adapted to overlap each other, means for detachably interlocking the edge of one section with the adjacent face of the complementary section, hanging bars loosely connected with the structure, and means for pivotally connecting said bars with the middle portion and means for connecting said bars with one corner of each section.

3. Means for closing an opening in a car or other supporting structure consisting of two complementary door-sections adapted to overlap each other, means for detachably interlocking the overlapped portions of said sections, hanging bars loosely connected with the supporting structure, adjustable connections between said bars and the central portions of said door-sections, and pivotal connections between one corner of each door-section and the supporting structure.

4. Means for closing an opening in a car or other supporting structure, comprising two complementary door-sections, means for interlocking said doors when in closed position, bars for hanging said doors from the structure, devices adjstably connecting said bars with said door-sections and means for locking said devices in their adjusted positions.

5. Means for closing an opening in a car, consisting of two independently-supported

complementary door-sections, a locking-bar rotatably mounted on one of said sections and means for engaging said bar, said means secured to the other section and adapted to 5 embrace said bar from opposite sides.

6. Means for suspending a car-door consisting of eyebolts pivotally mounted on said door, rods or bars loosely connected with said eyebolts and means for loosely connect-

ing the other ends of said bars with the car to overhead framing.

In testimony whereof we affix our signatures in presence of two witnesses.

JOSEPH J. VORHES.
HIRAM CRISMAN.
